UNITED STATES PATENT OFFICE.

LEVI B. EKAS, OF WILLIAMSTOWN, WEST VIRGINIA.

WELL-DRILLING MACHINE.

1,397,758.

Specification of Letters Patent. Patented Nov. 22, 1921.

Application filed August 12, 1919. Serial No. 316,934.

To all whom it may concern:

Be it known that I, LEVI B. EKAS, a citizen of the United States, residing at Williamstown, in the county of Wood and State 5 of West Virginia, have invented certain new and useful Improvements in Well-Drilling Machines, of which the following is a specification.

My invention relates to an improvement 10 in well drilling machines, and the object is to provide a structure which is perfectly rigid when erected, but which is capable of being readily dismantled when it is necessary to move the machine from one well to 15 another.

Another object is to provide a machine in which the power for operating the tools is applied in substantially a direct line.

Another object is to provide a machine 20 of few and simple parts so united and braced that the machine is made solid and rigid and substantially free of vibration, to the end that it can be used in the drilling of wells of great depth.

25 My invention consists in a machine having a framework which is in the main mortised, wedged and braced so that the main parts can be easily taken apart, when required.

30 It further consists in a main drive-shaft journaled in the frame and having a crank on each end, with means for applying the power at a point between the crank-case and substantially in direct line with the vertical 35 plane of the working tools, in connection with transmission mechanism mounted upon and adapted to be driven or not by said shaft, and means located between the cranks for clutching or unclutching the transmission, one crank being adapted to actuate the 40 walking-beam, and the other the spudding mechanism of the well drilling machine.

In the accompanying drawings:

Figure 1 is a side elevation;

45 Fig. 2 is a top plan view;

Fig. 3 is a view in front elevation with parts broken away;

Fig. 4 is a diagrammatic view of the base showing the location and arrangement of 50 the various posts and parts erected thereon;

Fig. 5 is a view of the hinge which connects the mast and the base;

Figs. 6, 7 and 8 are details.

The base is preferably composed of the 55 several mud sills 1, of which there are four shown laid transversely, and three other

sills, namely the main sill 2, the bull-wheel and sand-reel tail-sill 3, and the sub-sill 4 about midway between. Said main sill, bull-wheel and sand-reel tail-sill, and sub-sill, 60 are all preferably mortised in the four mud sills and held rigidly therein by means of the wedges 5 driven into the mortises of the mud sills alongside the main sill, bull-wheel and sand-reel tail-sill and sub-sill, 65 thus making a solid, rigid base structure, which is capable of being tightened up if, at any time, necessary, by merely driving the wedges farther in, and which can be dismantled and taken apart by driving the 70 wedges out.

Mounted on these sills are the various parts of the well drilling machine. Erected on the main sill and mortised and wedged thereto are the samson post 6, the jack-post 7, and the front bull-wheel post 8. While the jack-post and front bull-wheel post are preferably set up at right-angles to the main sill, the samson post is more or less inclined, and is set on the sill diagonally (as shown in Fig. 4) to provide for the walking-beam 7', which is pivotally supported thereon by the usual center-irons 8', and which in consequence extends in a direction diagonally to the main sill with its 80 forward end terminating at a point approximately midway between the main sill and the sub-sill.

Over the tops of the jack-post and front bull-wheel post the cap-sill 9 is bolted, and 90 its forward end extends to the samson post to which it is bolted, forming a brace for said part. As a further means of making these several posts rigid, the braces 10 and 11 are dropped into mortises in the main 95 sill, jack-post, cap-sill and samson post, and a brace 12 extending in the opposite direction is dropped into the mortise in the samson post and in the main sill, where it is held by the wedge 13, which thus holds 100 the several braces, hereinbefore mentioned, securely in place.

A side brace 14 is dropped into a mortise in the inner side of the samson post, and thence in a mortise in one of the mud sills, 105 and a brace rod 15 extends from the samson post diagonally to the sub-sill, and thus with the several braces the samson post as well as the jack-post and front bull wheel post are made perfectly tight and rigid.

Opposite the front bull wheel post 8 is the rear bull wheel post 16 mortised to the

bull-wheel and sand-reel sub-sill, and this post is made rigid by a brace 17 having its ends dropped in mortises in the sill and post, and a brace-rod 18 made tight by a 5 turn-buckle 20.

A bull-wheel shaft is journaled in the front and rear bull-wheel posts, and the operating cable 21 is secured to and adapted to be wound around this bull-wheel shaft. 10 Brake-wheel 22 is secured on this bull-wheel shaft, and a band brake 23 extends around the same and is connected to the bull-wheel and sand reel sub-sill where it is connected with a hand-lever 24, by which the operator 15 applies the brake.

A cross-brace 25 extends from the front to the rear bull-wheel post for bracing the two laterally, and this brace has a guide 26 which straddles the brake and brake-wheel, 20 thus supporting them laterally.

The sprocket-wheel 27 is secured on the bull-wheel shaft adjacent to and just within the cap-sill 9.

The main drive-shaft 28 is journaled in 25 bearings in the jack-post 7 on the main sill 2, and a corresponding post on the sub-sill 4, the latter having braces 29 mortised and wedged to make it rigid.

Secured on the main drive-shaft is a belt- 30 wheel 30 at a point between the supports which receives its power from a belt 31 from the engine or motor. Loosely mounted on the main drive-shaft is a sprocket-wheel 32, and a sprocket-chain 33 extends around the 35 two sprocket-wheels 32 and 27 for transmitting power from the former to the latter to drive the bull-wheel shaft. The clutch 34 is keyed to slide on the drive-shaft, and is adapted to clutch the sprocket-wheel 32 40 thereof when it is desired to withdraw the tools from the well and wind the cable 21 on the bull-wheel shaft.

There are two cranks 35 and 36 on the main shaft, one on each end, and a wrist-pin 45 37 is adapted to connect the connecting-rod 38 which extends to and operates the walking-beam and the crank 35, and spud cable 39 is adapted to extend from the main operating cable to the other crank 36 during 50 the spudding operation.

When spudding, the cross-brace 25 is removed, and the operating cable is passed under a removable pulley 40 journaled in a slot 41, in the forward end of the sub-sill. 55 This pulley is only used during the spudding operation, and it only has to be removed during the drilling operation, which is done by taking out pin 42 upon which it is journaled.

The numeral 43 represents the mast, which 60 may be made in two sections, as customary, and braced by the usual guys 44.

This has the usual crown pulley and sand reel pulley 45 and 46, only in my invention

the sand reel pulley is mounted at the extreme upper end of the mast, instead of on 65 the side as heretofore.

The mast, while resting upon the forward mud sill, is held there by hinge 47, which admits of its being swung down from its vertical position when the machine is to be 70 moved, or being swung back in place when the machine is set up for operation.

The sand-reel 48 is mounted at the rear, one end in a sliding bearing which is operated by the connecting-rods and link mechanism 50, 51, and the operating lever 52, and this reel is provided with a friction-drum 53 in position to engage the periphery of the drive-wheel. This sand-reel is also provided with a band-brake 54 which stops and holds 80 the reel when the friction-wheel is removed from engagement with the drive-wheel, it being understood that the brake is released when the drum is in engagement with the drive-wheel, and it is applied immediately 85 upon disengaging said wheel.

I claim:

1. The combination with a base and a mast, of a bull-wheel shaft, a cable secured to and wound thereon, a main drive-shaft 90 having cranks on each end thereof, a drive-wheel secured thereon between the cranks, a sprocket-wheel loosely mounted thereon, means for clutching said sprocket-wheel to the shaft, a sprocket-wheel on the bull-wheel 95 shaft, a sprocket chain extending over said sprocket-wheel, a cable adapted to extend from one of the cranks to the operating cable for spudding, a walking-beam and a connecting-rod extending from the walking-beam to the crank on the other end of the main drive-shaft, said drive-shaft with its cranks and transmission mechanism extending in the general line of operation of the operating cable. 100

2. The combination with a base, a mast, a bull-wheel shaft, an operating cable, a drive-shaft and a spudding cable, of a pulley journaled in a slot in the sub-sill of the base around which the operating cable extends 110 through the spudding operation, and a pin on which said pulley is mounted capable of being removed when the operating cable is to be used in the drilling operation. 105

3. The combination of a base, a mast, a 115 bull-wheel shaft and operating cable, posts secured to the base, diagonal and cross-braces and tension-braces, a drive-shaft having means of transmission thereon, cranks on opposite ends thereof, a walking-beam, 120 means for connecting the walking-beam to one of said cranks, and a spudding cable for connecting the other crank to the operating table.

In testimony whereof I affix my signature. 125
LEVI B. EKAS.
